(57) **CLAIM**

We claim the ornamental designs for a pendant switch for controlling a hoist, as shown and described.

DESCRIPTION

FIG. 1 is a perspective view of a pendant switch for controlling a hoist showing our new designs;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1.

FIG. 8 is a perspective view of another pendant switch for controlling a hoist showing our new designs;

FIG. 9 is a front elevational view of FIG. 8;

FIG. 10 is a rear elevational view of FIG. 8;

FIG. 11 is a left side elevational view of FIG. 8;

FIG. 12 is a right side elevational view of FIG. 8;

FIG. 13 is a top plan view of FIG. 8; and,

FIG. 14 is a bottom plan view of FIG. 8.
